UNITED STATES PATENT OFFICE.

JAMES W. PHELPS, OF CHICAGO, ILLINOIS.

ELECTRIC FLASHER.

Application filed February 17, 1926. Serial No. 88,969.

My invention relates to improvements in an electric circuit make and break device and has special reference to a simple flasher for use in a small capacity circuit, such as a string 5 of small incandescent lamps for decorative use such as is commonly used on Christmas trees. In such a string, or series of small decorative lamps, the lamps are connected in series, usually eight being used on a string 10 and collectively having a resistance sufficient for use on a 110 volt circuit.

To cause the lamps of such a string to flash it is only necessary to unscrew any one of the eight lamps, screw one of my flashers in the 15 socket and then screw the lamp into the outer end of the device. For this purpose the flasher is wound in series with the lamp and when the circuit is alternately made and broken it causes all of the lamps of the series to 20 flash in unison. By the use of several strings, each having its own flasher in circuit, a most beautiful kaleidoscopic effect can be produced and at a relatively small cost.

The object of my invention is to provide 25 such a device of such simple form and construction that it can be manufactured and sold for the purpose mentioned and at a price which shall be commercially successful.

My invention will be more readily understood by reference to the accompanying drawings in which:—

Fig. 1, is a diagrammatic view illustrating the application of my invention to a string of small decorative lamps;

Fig. 2, is an enlarged longitudinal, central, sectional view of a flasher made in accordance with my invention on the line 2—2 of Figs. 3 and 4;

Fig. 3, is a similar sectional view on the 40 line 3—3 of Figs. 2 and 4;

Fig. 4, is a transverse section on the line 4—4 of Fig. 2;

Fig. 5, is a view similar to Fig. 2 and showing a slight modification in construction and 45 taken on the line 5—5 of Fig. 6; and

Fig. 6, is a transverse section on the line 6—6 of Fig. 5.

In said drawings 1 illustrates a string of small decorative lamps 2 such as is commonly 50 used on Christmas trees, and 3 illustrates one of my small or midget flashers screwed into one of the small sockets 4 and the lamp screwed into the outer end of the flasher.

My improved small or midget flasher 55 comprises a metallic tubular shell 5 formed into

a screw socket 6 at one end for receiving one of the lamps 2 and formed at the other end into a screw plug 7 for screwing into the small sockets 4. This shell forms one side of the electric circuit for carrying the electric current.

For forming the central contacts for the plug 7 at one end and the socket 6 at the other end I provide a central member 8 of insulating material such as fibre, hard rubber, porcelain or the like and which has attached thereto the central contacts and the make and break device or mechanism. This member 8 is a flat strip and long enough to extend from the outer end of the plug 7 to 70 the base of the socket 6. The member 8 substantially fits edgewise within the tubular casing 5 and is adapted to be entered into the casing through the socket end of same. The member 8 may be held in the casing 5 by any 75 suitable means such as a pin 9 entering through the casing 5 and into the edge of the member 8. One end 10 of the member 8 is formed to project within the plug 7 and its extreme end 11 projects slightly beyond the 80 outer surface of an inturned flange 12 formed at the extremity of the plug and against which the adjacent end of the member 8 is shouldered. The member 8 is about one-fourth of the diameter of the shell 5, in thickness, for the purpose of providing space at 85 the sides of the member 8 for the contacts and flashing device.

At the plug end of the device the center contact 13 is formed of a thin strip of sheet 90 metal 14 secured to the member 8 by any suitable means such as the rivet 15 and bent over at its outer end slightly beyond the end of the member 8 to form the contact 13 so that it will be slightly yielding. At the opposite 95 end the central contact 16 is formed by a similar strip of sheet metal 17 secured rigidly to the member 8 by any suitable means such as the rivet 18 and formed with its inner end 19 bent back upon itself to receive an adjusting screw 20, the strip 18 being provided with suitable threaded openings for this purpose.

Upon the side of the member 8 opposite to the end 17 of the strip 16, I mount a very simple thermostatic make and break element 21. This element consists of a strip 22 of bimetallic sheet metal covered by a sheet of insulation material 23 and upon which is wound a current carrying wire 24 adapted to be heated when current passes through the 110

device and cause the alternate making and breaking of the circuit. The element 21 is rigidly mounted on the member 8 adjacent to the plug end of the device, as by rivets 25, 5 and the element is formed so that its body and opposite end 26 stand clear of the member 8. The free end 26 of the element 21 is provided with a contact 27 adjacent to the free end of the screw 20 and adapted normally to rest upon same and close the circuit preparatory to the initiation of the make and break action upon the beginning of a flow of current through the device. To complete the circuit through the device one end 28 of 10 the wire 24 is connected to the strip 14 forming the center contact 13 and the opposite end 29 is soldered to the free end of the bimetallic strip 22. The free end of the strip 17 which is bent over to form the center contact 16, is normally formed out of contact with the adjacent end of the member 8 to make it slightly yielding.

Preferably the tubular shell is encased within a tubular casing 30 of insulation material such as fibre or the like, and which extends from the outer end of the socket 6 to the base of the plug 7. The adjusting screw 20 projects through a free opening 31 in the tubular shell 5 and the outer casing 30 is 25 provided with a hole in which the screw 20 substantially fits and which construction practically dowels or secures the outer casing 30 upon tubular shell 5. By means of the adjusting screw 20 the frequency of the make and break action can obviously be adjusted or changed.

For some uses it is not desirable to permit any adjustment of the make and break device after it has been completed, and for this 40 purpose the form of device shown in Figs. 5 and 6 is provided. In this form the adjusting screw is eliminated, and instead of the contact strip 17 forming the center contact 16 being arranged on the opposite side of the member 8 from the thermo element 21, it is 45 arranged on the same side where it can con-

tact directly with the free end of the thermo element and thus complete the electric circuit. In this form, in order to retain the insulating casing 30 in place, it is secured by means of a doweling pin 32 which passes through the two shells and into the member 8, thus not only doweling the two shells together but also securing the member 8 against movement in the metallic tubular shell 5.

It will be seen that my improved make and break device is very simple in construction, that the make and break device comprising the member 8 and its attached contacts, including the thermo element, can be completed 60 as a unit and then entered into the shell 5, that the several parts of the device can be easily and quickly assembled and be held permanently in place and that the whole can be constructed or produced at a relative- 65 small cost.

As many modifications of my invention will readily suggest themselves to one skilled in the art, I do not limit or confine my invention to the specific details of construction 70 herein shown and described.

I claim:

A device of the kind described, comprising a metallic tubular shell formed into a socket at one end and a plug at the other, a flat bar 75 of insulation material fixed within the shell and extending centrally through the shell from the outer end of the plug to the base of the socket and presenting spaces on each side of the flat bar, bendable center contacts 80 for the plug and socket carried by the bar and projecting out from the ends thereof, and a thermostatic make and break element carried by the bar normally in contact with the center contact at one end and permanently connected with the center contact at the opposite end and adapted to intermittently make and break said normal contact.

In testimony whereof, I have hereunto set my hand, this 11th day of February, 1926.

JAMES W. PHELPS.
